UNITED STATES PATENT OFFICE.

ALFRED ROSENHOLZ, OF SAN FRANCISCO, CALIFORNIA, ASSIGNOR TO THE TRENTON IRON COMPANY, OF TRENTON, NEW JERSEY.

CABLE-TRAMWAY GRIP.

SPECIFICATION forming part of Letters Patent No. 650,590, dated May 29, 1900.

Application filed October 16, 1899. Serial No. 733,762. (No model.)

To all whom it may concern:

Be it known that I, ALFRED ROSENHOLZ, a citizen of the United States, residing in the city and county of San Francisco, State of California, have invented an Improvement in Cable-Tramway Grips; and I hereby declare the following to be a full, clear, and exact description of the same.

My invention relates to improvements in cable-tramway grips.

The object of my invention is to provide an improved conveyer and grip for cable-tramways, in which the load is carried upon a stationary cable and is gripped to a parallel moving cable.

My present invention is designed as an improvement upon Patent No. 495,374, issued to me April 11, 1893; and it consists in a means for mounting the gripping-jaws so that they are turnable and automatically adjustable to the line of travel of the cable upon which they are closed. Thus when the cables are running at a considerable incline up or down the weight being suspended vertically by gravitation will hang at a considerable angle with the line of the cable, and in order to make the grip effective and avoid kinks in the cable its automatic adjustment allows it to turn so as to follow the direction of the cable without reference to the position of the hanger and load.

My invention also comprises details of construction which will be more fully explained by reference to the accompanying drawings, in which—

Figure 1 is an end elevation of the apparatus. Fig. 2 is a side elevation, showing the apparatus at a release-station where the jaws are to be unclasped from the rope. Fig. 3 is an enlarged section transverse to the line of the rope. Fig. 4 is a front view of the same. Fig. 5 is a plan view. Fig. 6 is a modification showing a compound lever to actuate the grip.

A is a yoke or frame of any suitable description, from which the load or bucket B is to be suspended. Through the upper part of the frame of the yoke A pass the rods C, which are slidable approximately vertically through this yoke, and to the upper ends of these rods is swiveled a frame D, which carries the roll-

ers E. These rollers are adapted to travel upon the stationary supporting cable or track. In Fig. 2 they are shown as resting upon a section of track O, which is in the line with the cable upon which they travel and which forms a part of the release-station, to be hereafter described. The lower ends of the rods C are connected either directly or indirectly with a movable jaw F of the grip, this jaw being fulcrumed at f and having a lever-arm G extending approximately horizontally from it, so as to be actuated by the rods C. The connection between the jaw F and the rod C may either be direct, as shown in Figs. 1 to 5, or its lever-arm G may have its outer end acted upon by a supplementary fulcrumed lever G', as shown in Fig. 6, so as to produce a compound lever action to act upon the grip F with increased force, the rods C pulling upon the lever G' and the power from this lever being transmitted to the lever G and thence to the jaw F.

F' is a jaw which is stationary with relation to the fulcrumed and movable jaw so far as the opening and closing of the jaws are concerned; but this jaw is mounted upon or forms a part of a cylindrical sleeve II, which is turnable upon its horizontal axis in boxes I upon the main frame A. This revoluble sleeve is slotted vertically through the center, as shown at h, the slot being of sufficient length to allow ample movement of the lever-arm G, which actuates the grip.

The lower ends of the rod C are connected with the lever-arm G by means of a swivel-box J, which fits and is turnable upon the outer end of the lever G, this end being made cylindrical for that purpose. The box J has arms K extending outwardly from it, and to these arms the lower ends of the rods C are connected, as plainly shown in Figs. 3, 5, and 6.

By this construction, the weight suspended from the frame or yoke A being borne by the pulleys E, the slidable rods C, which are connected with the pulley-frame D, will allow the frame A to sink by reason of the weight, and this movement of the frame and the lower fixed jaw F' acts upon the movable jaw F through its lever-arms G or G' to close the jaw upon the traveling rope or cable P. At the same time by reason of the turnable or

2
swivel head H, which carries the lower jaw, the two jaws are allowed to turn about the axial line of this swivel part, so that when the direction of the cable changes either up 5 or down with relation to the hanger the change of angle of the traveling cable will be followed by the grips, which will thus always take a line of the cable and remain parallel with it whatever its changes of angle. The 10 distance to which the grips can turn or swivel in either direction may be determined by stops W. When the load arrives at a release-station, the supporting-pulleys E run upon the rigid supporting-track O. Beneath this 15 track is another rigidly-supported track R, so placed with relation to the frame A that a pulley S, journaled upon said frame, will run upon this track R, and the track O then declines and relieves the pulleys E of the weight, 20 which will then be supported upon the pulley S, thus leaving the pulleys E, traveling upon the track O, relieved of the weight of the load and free to sink by gravitation, and this acts, through the rods C, to push down 25 upon the levers G or G' and open the gripping-jaw F, thus releasing the cable and allowing it to continue running while the load stops.

Having thus described my invention, what 30 I claim as new, and desire to secure by Letters Patent, is—

35 1. In a cable-tramway conveyer, the trolley-frame movably carried thereon adapted to travel upon the cable, a pair of jaws adapted to engage with the movable cable, one of said jaws being movable, and mechanism connecting the trolley-frame with the movable jaw whereby motion is communicated to said jaw, a stationary jaw opposed thereto between 40 which and the movable jaw the cable is gripped, and a swivel-support for said jaws.

45 2. In a cable-tramway conveyer, a load-supporting frame, a movable trolley-frame, jaws adapted to grip a traveling cable, one of said jaws being movable and having connection between it and the trolley whereby it is closed upon the fixed jaw by the action of the weight, and a support for the gripping-jaws turnable in the load-carrying frame, whereby the jaws 50 automatically adjust themselves to the line of the cable.

55 3. In a cable-tramway conveyer, a load-supporting frame, a trolley adapted to travel upon a stationary cable, rods connected therewith slidably through the supporting-frame, a swivel-box with which the lower ends of said rods are connected, a fulcrumed gripping-jaw having a lever-arm, upon the outer end of which the swivel-box is turnable, and a sec-

ond jaw between which and the movable jaw 60 the traveling cable is gripped, said jaws being turnably connected with the load-suspending frame.

4. In a cable-tramway conveyer, trolley 65 mounted in a frame and adapted to travel upon a stationary cable, rods connected with the trolley-frame extending downwardly, a load-suspending frame vertically slidable with relation to said rods, a gripping-jaw mounted and turnable within the load-suspending frame and having a vertical central slot through its turnable head, a second jaw fulcrumed so as to open and close with relation to the first-named jaw having a lever-arm extending through the slot in the turnable head of the first jaw and swivel connections between the vertical rods and said lever-arm. 75

5. In a cable-tramway conveyer, the combination of the conveyer-frame and a trolley-frame movably carried thereon and adapted to travel upon a track or cable, a pair of jaws 80 adapted to engage with the moving cable and rotatively mounted to automatically adjust themselves to the line of the cable, one of said jaws being movable with relation to the other, a mechanism connecting the trolley-frame with the movable jaw whereby the latter is closed to grip the cable between it and the stationary jaw by the suspended weight, a 90 supplemental track disposed with relation to the main track or cable, and a pulley carried by the conveyer-frame adapted to ride upon said track to support the main frame so that the gripping-jaws are released from the traveling 95 cable.

6. In combination with a tramway-carriage frame, rods movably suspended therefrom, their lower ends suitably connected with an arm extending through a slotted cylindrical head, the front part of said arm and cylindrical head terminating as gripping-jaws, both being turnable as a whole on their horizontal axis transverse to the rope in channeled boxes or bearings bolted to the suspending-frame, a cable adapted to rest on the lower jaw, and gripped to the latter by the oppositely-movable jaw which terminates the horizontal arm or lever, and a semi-universal joint connecting said lever with the carriage-frame. 105 110

In witness whereof I have hereunto set my hand.

ALFRED ROSENHOLZ.
